PROCESS FOR CONVERTING HYDROCARBONS

Frederick E. Frey, Bartlesville, Okla., assignor to
 Phillips Petroleum Company, Bartlesville,
 Okla., a corporation of Delaware

Application November 22, 1932, Serial No. 643,919

7 Claims. (Cl. 196—10)

This invention relates to a process for the conversion of hydrocarbon gases into valuable normally liquid hydrocarbons by heating to a reaction temperature under high pressure.

It has been proposed to convert gaseous olefines, namely ethylene, propylene, and the butylenes into oils by heating under a pressure in excess of 500 pounds per square inch to a temperature of 700 to 1000° F., whereupon polymerization takes place and volatile normally liquid hydrocarbons are produced. It has been shown that the velocity of the polymerization reactions is greatly increased by increase in pressure, the formation of oils taking place rapidly, under partial pressures of olefines exceeding 500 pounds per square inch, at temperatures of 700—850° F. at which the cracking of gaseous paraffins is very slow.

It has further been proposed to convert the gaseous paraffins which are more refractory than olefines into normally liquid hydrocarbons by heating to a cracking temperature above 750° F. under a pressure of 500 or more pounds per square inch to effect a conversion into normally liquid hydrocarbons. When operating at elevated pressures I have found that, owing to the high temperatures required to effect an initial cracking of the gaseous paraffins to produce olefines, only a partial conversion into normally liquid hydrocarbons can be effected by a single exposure to a conversion temperature without the formation of tar and carbon, a great part of the paraffins surviving the conversion operation unchanged.

The object of the present invention is to increase the yield of normally liquid hydrocarbons obtainable from gaseous hydrocarbons in a single passage through the conversion unit, thereby increasing the efficiency of the process.

A further object is to convert olefinic hydrocarbons other than those formed in the conversion zone into an additional yield of liquid hydrocarbons.

Further objects will be apparent as the disclosure proceeds.

When ethane, propane, or butane is heated to a cracking temperature of 850—1100° F. decomposition takes place and smaller molecules, chiefly of the gaseous olefines, are produced. If the decomposition takes place under high pressure, the olefines are formed in high concentration and their polymerization into oils takes place rapidly, first with the formation of volatile oils, and, as the reaction proceeds, with the subsequent formation of heavy oils and carbon. The formation of heavy oils and carbon necessitates arresting the cracking before they are formed in sufficient

amounts to interfere with the economical operation of the process. Even in the conversion of butanes into oils the initial decomposition proceeds so much more slowly than the subsequent reactions under pressures in excess of 1000 pounds per square inch that the greater part of the butane must be discharged from the reaction zone unchanged, accompanied by about 8—14 per cent of higher boiling hydrocarbons, as well as similar amounts of the other gaseous paraffins and gaseous olefines. The primary decomposition of propane takes place at approximately one-third the rate of the butanes, and the conversion into oils is accordingly much less. Ethane yields even less oil than propane, while methane is substantially inert.

In the neighborhood of 1000° F. the rate of primary decomposition of propane and butane is increased approximately 3-fold by an increase in temperature of 50° F., while the rate of conversion into oils of the olefines produced by the aforesaid primary decomposition I have found to be increased approximately 2-fold by a 50° F. increase in temperature. Consequently, the velocity of the primary decomposition relative to the oil forming reactions is increased with increase in temperature, and I have found that, at the more elevated temperatures, an increased decomposition of paraffins may be obtained in a single exposure to a decomposition temperature before the conversion need be interrupted by reason of tar and carbon formation, and temperatures in excess of 1000° F., usually considered prohibitive in pressure cracking, give the best results.

The conversion of gaseous olefines into oils involves a sequence of changes into volatile oils, heavy oils, and finally carbon over the rather wide temperature range of 700 to 1500° F. or higher, but the nature of the oils formed is affected by the reaction to a marked degree. At the lower temperatures, 700 to 800° F., and elevated pressure, the aliphatic and alicyclic oils, I have found, are virtually the sole products of the polymerization, while at higher temperatures, oils of higher carbon content are formed, together with additional methane, the oils being largely aromatic when formed above 1200° F. The formation of aromatics and additional methane entails a loss in yield of oils at the higher temperatures, and the lower range of polymerization temperatures are accordingly to be preferred when a maximum yield is desired.

The present process achieves an increased yield of oils per pass through a coil by exposing gaseous paraffins under high pressure to a high re-

action temperature, preferably 1050-1250° F., for a time sufficiently long to effect a maximum decomposition into smaller molecules together with oils, but not long enough to permit excessive carbon and tar formation, then maintaining the reaction products, still under pressure, and at a polymerization temperature lower than the decomposition temperature for a time sufficient to effect a substantial further conversion into oils, chiefly aliphatic and alicyclic, at the lower polymerization temperatures.

An apparatus suitable for use in practicing the process is diagrammatically illustrated in the accompanying drawing, which shows a side elevation of a suitable apparatus.

In practicing the invention, normally gaseous hydrocarbons consisting chiefly of butanes, enter pipe A under a pressure of 1000-5000 pounds per square inch and pass continuously and at a high velocity through tube coil B of restricted cross-sectional area situated within furnace housing C wherein the hydrocarbons are heated to a reaction temperature preferably within the range 1050-1250° F. The hydrocarbons crack endothermally and, upon exposure to cracking temperature for a time sufficient to produce a high content of lower paraffins and olefines as well as oils, are discharged from coil B and may be partially cooled either by loss of heat or by the introduction through D of hydrocarbons at a lower temperature. The hydrocarbon is then exposed in reaction coil E, without any substantial further introduction of heat, to a polymerization temperature for a time sufficient to produce an additional yield of oils by polymerization of gaseous olefines. The reaction product containing oils and unchanged charging stock as well as lower gaseous hydrocarbons passes into a partial condenser F wherein a part of the butanes and the higher boiling hydrocarbons are separated and withdrawn at K. The vapors from F pass into fractionator G, wherein a condensate of butane and butene containing a controlled proportion of lower hydrocarbons is separated and withdrawn through pipe H and returned, together with butane distilled from the condensate withdrawn at K, to the conversion tube at A where it may be admixed with fresh charging stock. The vapors from G are discharged through partial condenser L in which gases containing the greater part of the methane are separated and released from the system at J, while a condensate containing the other light gaseous hydrocarbons, (principally ethane and propane), is released at I. The butanes are particularly suitable for conversion in the process, and the yield of oil is increased by the presence of gaseous olefines, entering either at A or D, or both. The lower paraffins, particularly methane and ethane, because of their high decomposition temperatures, are substantially inert in the presence of butanes and olefines, and detract from the efficiency of the process. For this reason, only a limited amount of the lower paraffins are best returned with butanes for retreatment, unless they are accompanied by substantial proportions of the desirable gaseous olefines.

Vapors containing substantial amounts of gaseous olefines are most suitable for introducing at D, particularly a concentrate from cracking still gases containing a large proportion of butylenes and butanes. The olefines are desirable since they enter into reaction and augment the yield of oils. A high proportion of such vapors can obviously be added if they are preheated

to a suitable degree. The lower hydrocarbons discharged from J and I are suitable for fuel or other uses; the material from I contains chiefly hydrocarbons higher than methane and is suitable for conversion into aromatic oils by cracking at high temperatures.

The endothermic cracking is best conducted at temperatures within the range 1050 to 1250° F. A tube of heat resisting alloy having a greatly restricted cross-sectional stream area permits high heat transfer coefficients and hence the short time of exposure which the use of high temperatures necessitates. Pressures of 1000 to 5000 pounds per square inch or more may be used, but I prefer to use a pressure of 2500-3000 pounds. The lower pressures necessitate the use of high temperatures in the polymerization operation with consequent loss of yield and increased formation of carbon, with the formation of oils of higher aromatic content. The duration of the endothermic cracking operation is preferably less than three minutes, but the conditions for conducting this operation are better defined by the temperature and composition of the issuing products, as set forth, since heat transfer considerations play a dominating part.

The polymerization step is preferably carried out at temperatures of from 800 to 1000° F.; the selection of the temperature depending chiefly on the result desired. The time of residence in the polymerization chamber is usually much greater than that required for the primary decomposition, in order to permit the optimum conversion into oils at the moderate temperatures required for developing the best yields of normally liquid hydrocarbons. The residence in the polymerization chamber should not be continued until excessive amounts of heavy oils are formed, and the duration of this step is usually from 5 to 30 minutes.

From the foregoing it is believed that the process may be readily understood by those skilled in the art, and it is manifest that changes may be made in the details set forth without departing from the spirit of the invention, as expressed in the following claims.

What is claimed and desired to be secured by Letters Patent is:

1. The process for converting hydrocarbon fluids predominantly paraffinic and of three and four carbon atoms per molecule into normally liquid gasoline hydrocarbons, which comprises continuously passing such a fluid at a temperature above about 1000° F. and under a pressure of 1000 to 5000 pounds per square inch through a heating zone of restricted cross sectional area for a time sufficiently long to effect a substantially maximum decomposition of some of the hydrocarbons of the fluid into smaller molecules, and a formation of some oils, but not long enough to permit substantial carbon and tar formation, then while maintaining the pressure, passing all the thermally treated fluid without further addition of heat through a zone wherein a reaction temperature below 1000° F. is maintained for a time sufficient to effect a substantial further formation of oils, then cooling the thermally treated hydrocarbons, and finally separating the normally liquid hydrocarbons.

2. The process for converting hydrocarbon fluids predominantly paraffinic and of three and four carbon atoms per molecule, into normally liquid gasoline hydrocarbons, which comprises continuously passing such a fluid at a temperature of about 1050-1250° F. and under a pressure

- of 1000 to 5000 pounds per square inch through a heating zone of restricted cross sectional area and thereby effecting the conversion of a substantial portion of the fluid into gaseous olefines and normally liquid hydrocarbons, then while maintaining the pressure, passing all of the thermally treated fluid without further addition of heat through a conversion zone wherein a reaction temperature of between about 800-1000° F. is maintained for a time sufficient to effect a substantial further conversion into oils, then cooling the thermally treated fluid, separating the normally liquid hydrocarbons from the same, also separating from the fluid a condensate of normally gaseous hydrocarbons predominantly of three and four carbon atoms per molecule, and returning said condensate to the heating zone.
3. A process for converting hydrocarbon material consisting essentially of propane and/or butane comprising subjecting said material to a temperature of about 1050-1250° F. and a pressure of 1000-5000 pounds per square inch, then admixing all the thermally treated material with hydrocarbon material containing a substantial amount of normally gaseous olefines, and then subjecting the resultant admixture to a temperature of about 800-1000° F. and a pressure of 1000-5000 pounds per square inch.
4. A two stage process for the non-catalytic conversion of normally gaseous paraffin hydrocarbons into normally liquid gasoline hydrocarbons comprising subjecting the initial hydrocarbons, in a first stage, to a pressure of 1000-5000 pounds per square inch and a temperature above about 1000° F., and then subjecting all the material from said first stage, in a second stage, to a pressure of 1000-5000 pounds and a temperature below 1000° F., said material being admixed with normally gaseous hydrocarbons prior to being subjected to said second stage.
5. A process for the conversion of hydrocarbon material consisting principally of butanes and propane into volatile normally liquid gasoline hydrocarbons which comprises subjecting said material to a temperature above about 1000° F. under pressure of 1000 to 5000 pounds per square inch for such a period of time as to permit the formation of olefin hydrocarbons without the formation of heavy oils and tars, then passing said material, without substantial reduction in pressure or separation of any of the reaction products, into a zone in which the said material is maintained at a temperature below 1000° F. for a period of time sufficient to polymerize the aforesaid olefins into volatile oils.
6. A process for the conversion of hydrocarbon material consisting principally of butanes and propane into volatile normally liquid gasoline hydrocarbons which comprises subjecting said material to a temperature above about 1000° F. under pressure of 1000 to 5000 pounds per square inch for such a period of time as to permit the formation of olefin hydrocarbons without the formation of heavy oils and tars, then passing said material, without substantial reduction in pressure or separation of any of the reaction products, into a zone in which the said material is maintained at a temperature between 800° and 1000° F. for a period of time sufficient to polymerize the aforesaid olefines into volatile oils.
7. A process for the conversion of hydrocarbon material consisting principally of butanes and propane into volatile normally liquid gasoline hydrocarbons which comprises subjecting said material to a temperature above about 1000° F. under pressure of 1000 to 5000 pounds per square inch for such a period of time as to permit the formation of olefin hydrocarbons without the formation of heavy oils and tars, then passing said material, without substantial reduction in pressure or separation of any of the reaction products, into a zone in which the said material is maintained at a temperature between 800° and 1000° F. for a period of time ranging from five to thirty minutes and thereby polymerizing the aforesaid olefines into volatile oils.
